UNITED STATES PATENT OFFICE.

NATHAN MORGESTERN, OF BROOKLYN, NEW YORK.

MOVABLE EYE FOR STUFFED TOYS.

Application filed March 29, 1922. Serial No. 547,614.

To all whom it may concern:

Be it known that I, NATHAN MORGESTERN, a resident of Brooklyn, Kings County, State of New York, and a citizen 5 of the United States of America, have invented certain new and useful Improvements in Movable Eyes for Stuffed Toys, of which the following is a specification.

This invention relates to improvements in 10 an eye mechanism for dolls or the like, but more particularly for stuffed dolls or bodies having a flexible or fabric covering stuffed with any suitable filling. My improved eye mechanism is particularly well adapted for 15 stuffed figures as will hereinafter be explained.

I will now proceed to describe my invention in detail, the novel features of which I will point out in the appended claims, reference being had to the accompanying drawing 20 wherein:—

Fig. 1 is a rear view of the plate portion of the casing for the eye;

Fig. 2 is a section on line 2—2 Fig. 1;

Fig. 3 is a rear view of the eye mechanism assembled;

Fig. 4 is a sectional view on line 3—3 thereof; and

Fig. 5 is a perspective view of the cover 25 portion of the casing.

To carry out one of the objects of my invention fully, I provide a cheap and efficient casing for an eye which can be attached directly to the sack, so to speak, 30 which contains stuffing, the sack, of course, being shaped in accordance with the figure to be produced, be it a doll figure, or an animal figure, such as a teddy bear. In the drawing, a casing member for an eye 6 is 35 illustrated comprising a plate 7, and cover 8, having a closed back 8a. The plate 7 is provided with an opening 9 to receive an eyelet 10. The eyelet serves to secure the plate 7 to the sack portion of the figure, a portion of such a sack portion being indicated by 11. The eye 6 extends partly 40 through the eyelet 10 and is pivotally supported by a trunnion member 12 secured at each end to the side walls 13 and 14 of cover 8. The eye carries a pin 15 in turn supporting a weight 16 of lead or other material heavy enough to move the eye upon 45 its pivotal pin 12 when the figure is tipped.

The plate 7 carries an inclined flange 17 at its upper end to receive flange 18 at the 55 upper end of cover 8. The plate 7 also carries side flanges 19 and 20 to engage the sides 21 of the box. The plate 7 is further provided with a flange 22 at its lower end for the bottom flange 23 of cover 8 to rest 60 against. The cover is snapped into place and depends, for its securement, upon a snug fit, no fastening means being employed. The cover keeps the stuffing 24 from interfering with the movement of eye 6. When 65 the cover is removed from plate 7, the eye comes away also which is obvious. The eye and plate are formed by suitable dies. My improved eye mechanism is extremely simple, is cheaply manufactured and quickly 70 assembled, all of which contributes to an extremely inexpensive durable eye mechanism for figures consisting of a stuffed pre-shaped sack. The plate 7 is secured to sack 11 by the eyelet 10 with the aid of an eye- 75 letting press.

What I desire to secure by Letters Patent is:—

1. In an eye mechanism for figures, comprised of a stuffed preshaped sack, a plate, 80 an eyelet to secure the plate to the sack, a cover having a closed back carried by the plate, and an eye pivotally supported within the cover and protruding through the eyelet.

2. In an eye mechanism for figures, comprised of a stuffed preshaped sack, a plate, an eyelet to secure the plate to the sack, a cover having a closed back carried by the plate, an eye pivotally supported within the 90 cover and protruding through the eyelet, and means to releasably secure the cover to the plate.

3. In an eye mechanism for figures, comprising a stuffed preshaped sack, a plate, an eyelet to secure the plate to the sack, an inclined flange on said plate, a vertical flange on said plate, an eye pivotally supported relatively to said plate, a cover for said eye, and flanges on said cover for engaging the flanges on said plate whereby said cover will be releasably held against said plate.

In testimony whereof I hereunto affix my signature.

NATHAN MORGESTERN.
